PLUG HANDLING APPARATUS FOR SEAMLESS TUBE MILL

George C. Kelly, Minneapolis, Minn., assignor to General Mills, Inc., a corporation of Delaware
Filed Sept. 9, 1963, Ser. No. 307,618
13 Claims. (Cl. 72—209)

This invention relates generally to apparatus used in the operation of a seamless tube mill. More particularly, this invention relates to a novel apparatus to be used in that portion of the seamless mill operation where a pierced billet or shell is fed through a plug rolling mill (which is part of the overall seamless tube mill) so as to be moved over a forming plug mounted on the front end of a mandrel, which novel apparatus functions to automatically replace the plug on the mandrel after each forming operation and to cool the several plugs used in sequence on the mandrel.

Seamless steel tubing has for many years been used commercially in great quantities (for example, the oil drilling industry uses it extensively) and there has been continuous effort to improve the operation of seamless tube mills with respect to general cost reduction, efficiency, safety, etc. Yet the present operation of a plug rolling mill requires a three man team: an operator for the hydraulic ram which pushes the pierced billet or shell into the work rolls; a plunger who with a large set of tongs suspended from an overhead cable removes one plug from the mandrel, drops this hot plug into a water bath and replaces it with a cool plug; and a roller who signals the ram operator and with a hook or set of tongs rotates the shell ninety degrees between a first and a second forming operations. (Sometimes the roller also does the work of the ram operator, thus making it a two man team.) The heat from the shells (which may be at a temperature of perhaps 1,900 degrees F.), the physical exertion required in handling these heavy plugs, and other factors make the working conditions for the plunger sufficiently severe so that a group of three pluggers are rotated (twenty minutes on and forty minutes off on each eight hour shift). With the plant operating on a twenty-four hour schedule, the labor expense alone in the operation of a plug rolling mill is considerable.

Also in such an operation, where the feeding in and feeding out of a large hot billet or shell must be coordinated with the movements of the plunger, there is, in attempting to keep a good steady pace of production, a danger in the ram operator or roller initiating one of these mechanical steps too closely after one of the operating movements manually performed by the plunger. For example, if the plunger should take ahold of a plug mounted on the mandrel, begin to remove the plug, and then hesitate to take a firmer grip with his tongs, there is a possibility that the roller will not be alert to this delay, and will cause the outfeed of the shell when the plunger is not clear of the outfeed path of the shell. To reduce the probability of such occurrences, the operating sequence must necessarily be performed with a certain degree of caution. Thus primarily for safety and also for considerations of better production, it would be a desirable improvement if this plug replacing operation could be performed without so exposing the workers to such dangers.

The plugs themselves are a source of some expense in the operation. For larger diameter pipe, the forming plug may weigh as much as two hundred pounds, and it must be maintained in a predetermined shape within reasonably close tolerances. With the plunger handling these plugs under the severe conditions as described above, occasionally a plug is dropped on the floor or

2

tumbled into the water bath improperly, thus damaging the plug or shortening its useful life.

Because of the difficulties and problems of the plug replacing operation of a plug rolling mill, various approaches have been taken to alleviate the same, either replacing the plug mechanically, replacing the plug and mandrel as a unit mechanically or devising other means which in some manner eliminate this manual handling of the plugs. But for various reasons, to the best knowledge of this applicant, none of these have met with any appreciable degree of commercial acceptance.

Accordingly, it is an object of the present invention to provide for a plug rolling mill a practical apparatus to accomplish mechanically the proper replacement and cooling of the forming plugs of a plug rolling mill.

It is a further object to provide such an apparatus which can readily be installed in the general type of seamless tube rolling mills commonly found in various commercial operations so as to require little adaptation of such existing mill installations, other than adding the apparatus of the present invention.

More specifically, my invention purports to accomplish the two previously mentioned objects by providing an improved apparatus comprising a plug manipulator, plug cooler, and mandrel positioner which cooperate in the following manner: the plug manipulator removing a hot plug from the mandrel and inserting it into a magazine of the plug cooler, and then receiving a cooled plug from the plug cooler and placing it on the mandrel; the plug cooler functioning to receive each of the hot plugs, move them through a water bath and deliver each of the thus cooled plugs in sequence to the manipulator; and the mandrel positioner, as its name implies, properly locating the mandrel so that a cooled plug can be inserted thereon.

These and other objects and features of the invention will be more readily understood and appreciated from the following detailed description of the preferred embodiment thereof selected for purposes of illustration and shown in the accompanying drawings, in which:

FIGURES 1 through 8 are semi-schematic drawings taken generally in side elevation with portions thereof shown in section, these figures illustrating the sequence of operation in a conventional plug rolling mill;

FIGURES 1A, 6A, and 7A are sectional views taken on, respectively, lines 1A—1A, 6A—6A, and 7A—7A of, respectively, FIGURES 1, 6 and 7, and illustrating the configuration and disposition of a pierced billet or shell during those portions of the operation illustrated in FIGURES 1, 6 and 7;

FIGURE 2A is a transverse sectional view taken on line 2A—2A of FIGURE 2 to illustrate the configuration of the work rolls of a conventional plug rolling mill;

FIGURE 9 is a top plan view, illustrating in full lines 55 the boom in its full left loading and unloading position, and in broken lines its full right plug replacing position and its intermediate working position. For clarity, a positioning jack shown in perspective in FIGURE 14 is omitted; also the bridge is shown partly in section as indicated at line 9—9 of FIGURE 14.

FIGURE 10 is a view taken on line 10—10 of FIGURE 9;

FIGURE 11 is a side elevational view of the apparatus of the present invention, with the bell housing of the seamless tube mill shown in section, and the work rolls and the mandrel being shown in broken lines;

FIGURE 12 is a rear elevational view of the apparatus of the present invention;

FIGURE 13 is a perspective view of the plug cooler portion of the apparatus of the present invention;

FIGURE 14 is a perspective view of the manipulator of the present invention;

FIGURE 15 is a fragmentary side elevational view of the manipulator boom of the present invention, with portions thereof shown in section;

FIGURE 16 is a front elevational view taken at line 16-16 of FIGURE 15, and

FIGURE 17 is a longitudinal sectional view taken on line 17-17 of FIGURE 16.

It is believed a clearer understanding of the present invention will be attained by first indicating the apparatus and operating procedure now commonly used in conventional plug rolling mills; then describing the structure of the plug manipulator and mandrel positioner of my invention, and the manner in which these components cooperate with the conventional existing apparatus of a plug rolling mill; and finally describing the structure and operation of the plug cooler of my invention and pointing out the manner in which this plug cooler cooperates with the plug manipulator and the existing plug rolling mill apparatus.

Before a steel billet is delivered to the plug rolling mill portion of the overall seamless tube milling operation, the billet has been heated to about 1,900 degrees F., and then passed a couple of times through a piercing mill. In the piercing operation, the billet is fed by rollers onto a piercing mandrel to form a hole in the billet to give it the overall configuration of a cylindrical shell. After the piercing operation, the billet is reheated and then rolled down a ramp into a trough formed in a stationary bed, at which trough location the billet begins to be processed through the plug rolling mill, for which the apparatus of the present invention is provided.

The sequence of operation of a typical prior art plug rolling mill (not considering for the moment the apparatus of the present invention) is illustrated schematically in FIGURES 1 through 8. Numeral 10 designates the aforementioned bed having the receiving trough 12 in which the pierced billet or shell 14 is deposited after having been reheated subsequent to the piercing operation. Aligned with, and located behind, the trough 12 is a pneumatic cylinder 16 having a ram 18, which (as illustrated in FIGURE 1 and 2) functions to push the shell 14 through a bell housing 20, which guides the shell 14 onto a forming plug 22 located between continuously rotating upper and lower work rolls 24 and 26, respectively, and mounted on the free rear end of a mandrel 28.

These work rolls 24 and 26 are large, heavy, generally cylindrical metal pieces, formed with matching rounded circumferential grooves 30 and 32 (as illustrated in FIGURE 2A) in which the rolls 24 and 26 grip the shell 14. These rolls 24 and 26 function to shape the shell 14 over the plug 22 by moving it over the plug 22 and mandrel 28. After the work rolls 24 and 26 have so gripped the shell 14, the ram 18 retracts (as indicated in FIGURE 3). Several guideways 34 are provided along the length of the mandrel 28 so as to properly support the shell 14 circumjacent the mandrel 28. When the shell 14 has reached its furthest "in" or forward position of travel (as shown in FIGURE 4), the forming plug 22 is manually removed from the mandrel 28 in the afore-described manner (the plunger gripping with a pair of tongs a protruding nose piece 36 of the plug 22 and pulling the plug 22 off the mandrel 28).

When the plunger has so removed the plug 22, the man who works as the roller pushes a control button which opens the work rolls 24 and 26 and causes a pair of continuously rotating stripper rolls 38 and 40, respectively, located forward of, and constructed similarly to, the work rolls 24 and 26, to grip the shell 14 (as illustrated in FIGURE 5) and move the shell 14 (as illustrated in FIGURE 6) "out" or rearwardly and into the trough 12 formed in the bed 10. The speed with which the stripper rolls 38 and 40 eject the shell 14 is sufficient to carry the shell 14 to its furthest rearward or out position in the trough 12.

At this time, the plunger, having deposited the hot

plug 22 in a water bath, now takes with the tongs a cool plug 22 and places the same onto the end of the mandrel 28. At the same time the roller takes hold of the ejected shell 14 with a hook or a pair of tongs and rotates the shell 14 ninety degrees (from the position shown at 6A to that shown at 7A), preparatory for a second plug rolling operation. This is done to eliminate the longitudinal bulges or concentrations of material 42 formed on each side of the shell 14 on its first pass through the plug rolling mill, this being illustrated in the sectional views of the shell 14 in FIGURES 6A and 7A. When the cool plug is positioned on the mandrel 32 (as shown in FIGURE 7) and the plunger is clear of the path of the path of the shell 14, the roller signals the ram operator, and the shell 14 is again fed into the work rolls 24 and 26 (which are now closed) by means of the ram 18 (as illustrated in FIGURE 8). After this second plug rolling operation, the ejected shell 14 is moved from the trough 12 to another station where the shell 14 is put through a subsequent reeling operation.

To describe now the apparatus of the present invention, numeral 50 designates generally the plug manipulator of this invention, which manipulator comprises a stationary bridge 52 disposed above and transversely of the feed path of the shell 14 in the plug rolling mill, and a carriage 54 mounted for back and forth movement along the length of the bridge 52 (i.e. transversely of the feed path of the shell 14). The bridge 52 is rigidly mounted from the floor or other stationary surrounding structure and is constructed as a horizontally disposed frame having a generally rectangular configuration. The two longitudinal frame components are a pair of I beams 56, each of which provides a suitable track for heavy duty wheels 58 mounted on the carriage 54. The I beams 56 are joined at each end by cross pieces 60 of the bridge frame, and are braced at intervals along the length thereof by cross braces 62 welded or otherwise secured to the top side of the I beams 56.

Located between the I beams 56 of the bridge 52 is a generally rectangular upper carriage frame 64 on each side of which are mounted the aforementioned carriage wheels 58 which track to the I beams 56. Rigidly fixed to and depending from the carriage frame 64 is a sturdy hopper-shaped support structure 66 which has rigidly fixed to its lower end a carrying member 68 for a manipulator boom 70.

This boom 70 comprises generally a stationary piston member 72 and a cooperating cylinder member 74, the latter being mounted for reciprocating longitudinal slide movement in a suitable slide journal formed in the carrying member 68 at the lower end of the supporting structure 66. Fixed to and extending rearwardly from the carrying member 68 are a pair of channel pieces 78 which are joined at their ends by a front cross piece 80, to which is fixed the tail end of a tubular piston rod 82. It is from this cross piece 80 that the piston drives the cylinder boom 74. Fixed to the head end of this rod 82 is the piston head 84 of the piston member 72, this piston head 84 being located within the cylinder 74.

To supply a drive fluid (either compressed air or a hydraulic fluid) to the boom 70, there is located concentrically within the rod 82 a feed line 86 leading through the piston head 84 so as to communicate with the head chamber 88 defined by the cylinder 74 and the piston head 84. The annular passage 90 defined by the piston rod 82 and the outer surface of feed line 86 communicates with the tail chamber 92 (also defined by the cylinder 74 and piston head 84, but also containing the rod 82) at a location adjacent the piston head 84. This annular passage 90 communicates with a feed line 94 through a sealed chamber 96 defined by the cross piece 80.

The nose or working end of the boom cylinder member 74 is directed forwardly and carries thereon a gripping head, generally designated 100, by which the boom 70 grips each of the forming plugs 22. The housing 102

for this gripper head 100 is fixed to the front end of the cylinder member 74 and is provided with a plurality of radially disposed longitudinal slots 104, each of which accommodates therein a related gripping finger 106, likewise disposed longitudinally and arranged in a regular pattern about the circumference of the housing 102. Each of the fingers 106 is pivotally mounted at 107 in its related slot 104 about an axis transverse to the longitudinal axis of the cylinder member 74 and generally tangential to the circumference of the housing 102.

To cause the tips 108 of the fingers 106 to converge in a gripping movement toward the center axis of the cylinder member 74 there is provided a cam plug 110 disposed within the housing 102 to engage the base end 112 of the fingers 106. Extending rearwardly from the cam plug 110 is a drive screw 114 which is moved longitudinally in the housing 102 by means of a drive nut 116 which is turned by an electric or fluid operated reversible motor 118 located in the housing 102. Rearward motion of the cam plug 110 causes the fingers 106 to grip the plug nose piece 40, while forward motion of the plug 110 permits a spring 120 to push a positioning block 121 to spread the finger 106 and release the plug nose piece 36. At the rear of the housing 102 is a transverse bulkhead 122 which isolates the jaw mechanism 100 from the head chamber 88 in the cylinder member 74. To drive the motor 120, suitable feed lines 124 (either electric or hydraulic) are provided in the wall of the cylinder member 74 and reach outwardly from the rear end thereof to connect to a suitable source of drive fluid.

The carriage 54 is moved along the length of the bridge 52 by means of a cylinder 126 fixed to the upper carriage frame 64 and driven from a stationary piston head 128 at the mid-length of the bridge 52. Extending longitudinally of the bridge 52 and reaching in opposite direction from the piston head 128 are a pair of piston rods 130 and 132, each of which joins to a related end piece 60 of the rectangular bridge frame 52. The piston head 128 partitions the interior of the cylinder 126 into two chambers 134 and 136, each of which communicates through the piston 128 with a related fluid supply passage formed in the interior of, respectively, piston rods 130 and 132. Thus by supplying fluid to either of the rods 130 or 132 the carriage 54 can be driven in either direction along the length of the bridge 52.

As will be described more fully hereinafter (and as shown in FIGURE 9), the carriage 54 has three operating positions, namely: a full right position at which the boom 70 is either placing a plug 22 on the mandrel 32 or withdrawing it therefrom, a full left position where the plug cooling magazine (to be described hereinafter) is either taking a hot plug 22 from the boom 70 or supplying a cool plug 22 thereto, and an intermediate position at which the boom is stationed while the pierced shell 14 is being fed onto the forming plug 22 and onto the mandrel 32, from which station the boom 70 will follow the tail end of the pierced shell 14 toward the plug 22 before the tail end of the shell 14 has passed over the plug 22.

To properly decelerate the carriage 54 as it travels to either of the extreme end positions on the bridge 52, the bridge 52 is provided with a pair of cam switches 138 and 140 each of which is engaged by an actuating cam or by a related carriage wheel 58 respectively, mounted on carriage frame 64. To stop the carriage 54 at its intermediate position, there is provided a pair of retractable stops 146 pivotally mounted on a suitable cross beam 148 reaching between the I beams 56. The two stops 146 are caused to pivot into the path of the carriage frame 64 by extending a hydraulic or air actuated jack 150 connected at each end to a related one of the stops 146. Each of the stops 146 is provided with a related one to limit pieces 152 mounted from the beam 148 to insure that both stops 146 are in the path of the carriage frame 64 when the jack 150 is fully extended. The carriage

frame 64 is provided with a pair of shock absorbers 154 to engage each of the stops 146. With the carriage 54 so halted by the stops 146, the drive fluid that enters the carriage actuating cylinder 126 is merely bypassed through a suitable relief valve in the hydraulic system. Retraction of the jack 150 causes the stops 146 to swing up and out of the path of the carriage frame 64.

To indicate generally the sequence in which the carriage 54 moves to these three operating positions, assuming that the carriage has been halted by the stops 146 at its intermediate position (i.e. moderately to the left, as seen in FIGURE 9, of the feed path of the billet 14) and that the billet or shell 14 has reached the operating position indicated in FIGURE 3 (i.e. beginning to be drawn inwardly by the work rolls 24 and 26 and the ram 18 withdrawing from the billet 14), the operating sequence is initiated by the rear end of the billet 14 passing by an infrared detector 156 which is mounted from the floor or other stationary object in the desired position. When the ram 18 has retracted sufficiently and the shell 14 has moved a sufficient distance forward (the detector 156 ascertaining this by sensing the abrupt reduction in intensity of heat rays transmitted thereto), fluid is caused to flow through line 130 into the chamber 134 of the cylinder 126 so that the carriage 54 moves quickly toward its full right position (i.e. with the boom aligned with the feed path of the shell 14). Also fluid flows rapidly into the head chamber 88 of the boom cylinder 74 so that the head 100 of the cylinder member 74 overtakes the rear end of the shell 14 and actually reaches into the rear end of shell 14 to center on the protruding nose piece 36 of the plug 22 on the mandrel 32 before the rear end of the shell 14 has cleared the forming plug 22. The purpose of this is to enable the head 100 to engage the plug nose piece 36 while the pierced shell 14 is yet engaging the plug 22 so as to properly center the same.

When the shell 14 has moved forwardly to the extent that it clears the plug 22 on the mandrel 32 (as in FIGURE 4), the boom 70, by means of its gripping head 100, engages the nose piece 36 of plug 22 and withdraws the plug from the mandrel 32. The carriage 70 moves to its full left position (the stop 146 having been retracted by the jack 150), and the cylinder member 74 of boom 70 moves rearwardly to its fully retracted position. By the time the carriage 54 approaches its full left position, the cylinder 74 is fully retracted so that the plug 22 carried in the gripper head 100 is deposited in the magazine of the plug cooler 200 (to be described hereinafter). The carriage 54 and the boom 70 remained at this full left position, while the plug cooler 200 removes the hot plug 22 and places a cool plug 22 into the gripper head 100. The gripper head 100 closes on this plug 22 and as the carriage 54 moves to its full right position, the boom 70 begins to extend, to transport this plug 22 to the mandrel 28.

It is to be noted that when the plug manipulator 50 moves its head 100 to grip the hot plug 22 on the mandrel 32, the plug is centered by the pierced shell 14, which is in turn located by the work rolls 24 and 26. However, when the plug manipulator 50 is carrying a cool plug 22 to the mandrel 32, this mandrel 32 is unsupported along its length, and has a tendency to sag. For this reason, there is provided mandrel positioner, generally designated 160, comprising a V-block 162 located beneath the mandrel 28. This V-block 162 is hydraulically actuated by a related jack 164 so as to be moved upwardly to engage the mandrel 28 and center the same. When the plug manipulator 50 has deposited the cool plug 22 on the front end of the mandrel 28, and the carriage 54 begins to withdraw to its intermediate location, the V-block 162 drops away from the mandrel and another billet 14 (or the same billet 14 making its second pass through the plug rolling mill) is moved by the ram 18 onto the cool plug 22 now positioned on mandrel 28.

The plug cooler 200 provided by the present invention, comprises a water tank 202 in which is mounted for longitudinal movement along, and rotary motion about, an axis paralleling the longitudinal axis of the manipulator boom 70, a plug magazine 204.

Before describing in detail the structure and operation of this plug cooler 200, it should be indicated that each plug 22 comprises a body 206 which provides the forming surface about which the shell 14 is shaped, and a plug mounting piece 208. (This is illustrated in FIGURE 11.) This piece 208 comprises a generally circular mounting flange 210 which fits in a mating recess 210a in the rear of the plug 22, and a pair of aligned dowel pins 212 and 214 which extend oppositely from the center of the flange 210 and are disposed perpendicular thereto. The one pin 212 extends through and beyond the plug body 206 and protrudes therebeyond to provide the aforementioned nose piece 36 by which the plug 22 is gripped by the manipulator gripping head 100, while the other pin 214 fits in a mating socket in the free end of the mandrel 28, to provide a suitable mounting therefrom. Throughout the entire operation, the plug body 206 and the plug mounting piece 208 of each plug 22 remain together.

The aforementioned plug magazine 204 comprises two parallel, transversely disposed circular plates 216 and 218, longitudinally spaced and aligned with respect to one another and both fixedly secured to a longitudinal shaft 220, which in turn is journal mounted at the front and rear of the tank 202 (as at 222 and 224, respectively) for longitudinal and rotary motion. Evenly spaced about the peripheral portions of the plates 216 and 218 are a plurality of pairs (six herein) of matching slots 226 and 228, which open to the circumference of plates 216 and 218, each slot 226 and 228 disposed to receive, respectively, dowel pins 214 and 212 of a related plug 22.

These slots 226 and 228 are so angled with respect to the radial lines of plates 216 and 218 that when the magazine 204 is disposed with two pairs of slots 226 and 228 uppermost, the pair of slots 226 and 228 which are at the upper location nearest the manipulator boom 70 (this, as described hereinafter, being the load and unload station) are disposed horizontally and open toward the manipulator boom 70. Thus the boom 70 can, simply by moving a plug 22 laterally, insert the plug into, or remove the plug 22 from, the magazine 204, with the dowel pins 214 and 212 fitting into the related slots 226 and 228, with the plug body 206 fitting partially between the magazine plates 216 and 218.

Located in the water tank 202 and positioned, respectively, in front of and in back of the plug magazine 204, are a front and a rear spider frame 230 and 232, each having a plurality of socket members 234 and 236, respectively, which correspond in number and location to the slots 226 and 228 in the magazine 204, so as to interfit with, respectively the front and rear pins 214 and 212 of the plugs 22 and thus hold these plugs 22 in the magazine 204. To enable the plugs 22 to be loaded into and unloaded from the magazine 204 laterally, the rear spider 232 has no socket member at the load and unload station. The rear spider 232 is fixedly located in the tank 202, while the front spider 230 is longitudinally fixed, but is rotatably mounted by means of a collar 238 about the shaft 220. It is this collar 238 which provides the slide and rotary journal for the shaft 220, and this collar 238 is itself mounted for rotary motion about the axis of the shaft 220 in a mounting post 240.

Fixedly secured to the front end of the collar 238 is a radially disposed lever arm 242 by which an indexing jack 244 (i.e. a cylinder and a piston operatively disposed therein) rotates the collar 238 (and consequently the front spider frame 230) in sixty degree increments. To move the shaft 220 longitudinally either toward the rear spider 232 or forwardly toward the front spider 230, there is provided a longitudinally disposed fluid actuated

jack 246 which engages the rear end of the shaft 220 through a thrust bearing 248, this jack 246 being mounted from a suitable support frame 250.

The front spider frame 230 is provided (see FIGURE 13) with an indexing plate 252 having a plurality of holes 254 arranged to interfit with corresponding indexing pins 256 fixed on the back face of the front magazine plate 218.

The water tank 202 is provided with a suitable cold water inlet 258, and an outlet 260. The latter is arranged so as to maintain the water level in the tank moderately above the rotary axis of the shaft 220 but below the uppermost part of the plug magazine 204. Thus as the magazine 204 rotates through increments of sixty degrees, four plugs 22 are at all times immersed in the cold water bath of the water tank 202.

To describe the operation of this plug cooler 200, it will be assumed that the manipulator boom 70 has withdrawn a hot plug 22 from the mandrel 32 and is carrying the same toward the plug cooler 200, the longitudinal jack 246 has pushed the magazine 204 to its furthest rearward position, so that each of the plugs 22 contained in the magazine 204 is free of the front indexed spider 230 but engages each with its one dowel pin 212 a related socket 236 of the rear spider 232, so that each of the plugs 22 is held in a related pair of magazine slots 226 and 228.

The slots 226 and 228 at the upper portion of the magazine 204 nearest the manipulating boom 70 (i.e. at the load and unload station) are empty, while each other pair of slots 226 and 228 carries a plug 22. When the manipulating boom 70 reaches the plug cooler, it is fully retracted, and the hot plug 22 carried in the gripper head 100 is slipped into the magazine slots 226 and 228 at the load and unload station. The gripper head 100 of the boom 70 releases, and the longitudinal jack 246 is actuated so as to pull the magazine 204 forwardly. As the magazine 204 so moves forwardly, the dowel pins 214 of each of the plugs 22 in the magazine engage a related socket member 234 in the front spider 230, as the rear dowel pins 212 disengage their related socket members 236 in the rear spider 232. Thus throughout this forward movement of the magazine 204, each of the plugs 22 and the magazine 204 are continuously engaged by either a front or rear socket member 234 or 236, so that the plugs 22 are held in their proper locations in the magazine 204.

When the magazine 204 is fully retracted, the indexing pins 256 have engaged the indexing holes 254 in the indexing plates 252. Then the indexing jack 244 rotates the collar 238 and consequently the plate 252, and the magazine 204 through a 60 degree increment of travel.

Immediately after this, the longitudinal jack 246 moves the magazine 204 rearwardly in the tank, so that a cool plug 22 which has now been lifted from the water bath to the load and unload station is pushed forward with the dowel pin 212 of this plug 22 being inserted into the gripper head 100 of the manipulating boom 70. The jaw mechanism 100 then closes on the dowel pin 212 of this cool plug 22, and as the carriage 54 moves laterally, this plug 22 moves from its load and unload station carried by the boom 70.

It is to be understood that each of the aforescribed moves of the manipulator 50 and the plug cooler 200 may be initiated by an operator manually moving appropriate controls, or automatically by each movement of the apparatus engaging a switch to open a valve to initiate the subsequent operating movement. Also, the operation may be accomplished part manually and part automatically, with the operator initiating various portions of the operating sequence. Since such arrangements of control apparatus are well known in the prior art, no attempt has been made to illustrate or describe the same.

It should be understood that the foregoing is merely illustrative of certain embodiments of the invention and

many variations may be made by those skilled in the art without departing from the spirit and scope of the invention.

Now therefore, I claim:

1. In a plug rolling mill, where a billet is fed along a longitudinal feed path over a replaceable plug mounted at a working location on the rear end of a longitudinally aligned mandrel, an apparatus to replace a hot plug on the mandrel with a cool plug and to provide for cooling plugs used in rotation in the plug rolling mill, said apparatus comprising, in combination:

- (a) a plug manipulator comprising a boom having a plug gripper attached to one end thereof, said boom being mounted from a carrying frame in a manner to be movable longitudinally with respect to said frame, and transversely between said working location and a plug transfer station which is spaced transversely from said feed path, and comprising power means to so move said gripper between said working location and said plug transfer station,
- (b) a plug cooler located at said plug transfer station comprising a plug carrier having a plurality of plug holding means, each arranged to receive a related plug from and to deliver said related plug to said manipulator, said carrier being movable along a predetermined course in which each of said plug holding means in sequence moves its related plug from said transfer station, through a cooling zone and back to said transfer station.

2. The apparatus as recited in claim 1, wherein there is a mandrel positioner for supporting the mandrel comprising locating means movable transversely to engage said mandrel and hold said mandrel in alignment with said longitudinal feed path.

3. The apparatus as recited in claim 2, wherein said mandrel positioner comprises block means having a recess to receive said mandrel and means to move said block generally vertically to lift said mandrel into a position in alignment with said feed path.

4. The apparatus as recited in claim 1, wherein the boom is mounted for movement along a direction aligned with said feed path, so that said gripper is able to reach into the rear end of said billet and grasp said plug in its working position before the billet has cleared the plug.

5. The apparatus as recited in claim 1, wherein said manipulator comprises:

- (a) a carrying frame providing horizontally and transversely aligned rail means,
- (b) a carriage mounted on said rail means for horizontal transverse movement therealong,
- (c) a manipulator boom mounted on said carriage for longitudinal movement toward and away from said plug in its working position,
- (d) said plug gripper being mounted on the front end of said boom.

6. The apparatus as recited in claim 1, wherein each of said plug holding means comprises slot means in said plug carrier, each of said slot means being so arranged as to open transversely toward said manipulator gripping means so as to be able to receive its related plug by said manipulator moving said related plug transversely into said slot means at said transfer station.

7. The apparatus as recited in claim 6, wherein said plug carrier is movable longitudinally to and away from said transfer station, so that a hot plug can be taken from said manipulator and a cold plug delivered thereto by longitudinal movement of said plug carrier.

8. The apparatus as recited in claim 7, wherein said plug cooler comprises front and rear plate means, each of which has a plurality of peripherally located slots, each slot matching a related slot of the other plate means so that there are a plurality of pairs of a front and a rear slot to receive respectively a front and rear pin of a related plug, said plug cooler having a front and a rear locating frame, each frame provided with socket means

for receiving said pins, said front frame being located in front of said front plate means and said rear frame being located behind said rear plate means, and said plate means being movable between a front position proximate said front frame and a rear position proximate said rear frame, whereby at least one or the other of said frames is performing a pin engaging function so that said plugs are each held in its related pair of slots.

9. The apparatus as recited in claim 8, wherein said front frame is rotatably mounted about its longitudinal axis and there are means to so move said front frame in predetermined increments about its longitudinal axis so that each of said plugs can be moved from its transfer position through said cooling zone and back to said transfer station.

10. The apparatus recited in claim 1, wherein said plug cooler comprises:

- (a) a cooling means defining a cooling zone and providing a cooling medium in said cooling zone,
- (b) a magazine comprising a pair of longitudinally spaced and aligned plate means, the general plane of each plate means being transversely disposed, said plate means being secured to one another and rotatable about a longitudinal axis,
- (c) each of said plate means being provided with a plurality of outwardly disposed peripheral slots, each of which matches with a related slot of the other plate means, so that there are matching pairs of longitudinally aligned front and rear slots, the front slot of each pair being arranged to receive a related front pin of a related plug with the rear slot in a similar manner being disposed to receive a rear pin of said related plug,
- (d) a front and a rear plug pin receiving frame, the front frame being located in front of the front plate means and the rear frame being located behind rear plate means, each of said frames having a plurality of evenly spaced sockets to receive a related plug pin to hold said plugs in said magazine,
- (e) means to move said magazine longitudinally between said front and rear frame, at least one of said frames holding said plugs at all times as the magazine moves longitudinally, and
- (f) means to rotate said magazine in predetermined increments so that each pair of slots, carrying a related plug, moves in sequence to said transfer station.

11. The apparatus as recited in claim 10, wherein said plug cooling means comprises a fluid containing tank and said magazine is so disposed with respect to said tank as to be partially submerged in the fluid contained in said tank.

12. The apparatus as recited in claim 10, wherein said means to rotate said magazine comprises power means operatively connected to said front plug pin holding frame, so that said magazine is rotated only in a forward position when operatively engaging said front frame.

13. In a plug rolling mill, where a billet is fed along a longitudinal feed path over a replaceable plug mounted at a working location on the rear end of a longitudinally aligned mandrel, an apparatus to replace a hot plug on the mandrel with a cool plug and to provide for cooling plugs used in rotation in the plug rolling mill, said apparatus comprising, in combination:

- (A) a plug manipulator comprising:
  - (a) a carrying frame providing horizontally and transversely aligned rail means,
  - (b) a carriage mounted on said rail means for horizontal transverse movement therealong,
  - (c) a manipulator boom comprising a cylinder mounted for longitudinal slide movement with respect to said carriage, and a piston operatively disposed within said cylinder and secured to said carriage so as to enable said cylinder to move longitudinally,

11

- (d) a plug gripper mounted on the front end of said cylinder,
- (B) a mandrel positioner comprising locating means movable transversely to engage said mandrel and hold said mandrel in alignment with said longitudinal feed path, 5
- (C) a plug cooler comprising:
  - (a) a cooling tank to contain a cooling fluid at a predetermined level,
  - (b) a magazine comprising a pair of longitudinally spaced and aligned plate means, the general plane of each plate means being transversely disposed, said plate means being secured to one another and rotatable about a longitudinal axis, 10
  - (c) each of said plate means being provided with a plurality of outwardly disposed peripheral slots, each of which matches with a related slot of the other plate means, so that there are matching pairs of longitudinally aligned front and rear slots, the front slot of each pair being arranged to receive a related front pin of a related plug with the rear slot in a similar manner being disposed to receive a rear pin of said related plug, 15

12

- (d) a front and a rear plug pin receiving frame, the front frame being located in front of the front plate means and the rear frame being located behind rear plate means, each of said frames having a plurality of evenly spaced sockets to receive a related plug pin to hold said plugs in said magazine,
- (e) means to move said magazine longitudinally between said front and rear frame, at least one of said frames holding said plugs at all times as the magazine moves longitudinally, and
- (f) means to rotate said magazine in predetermined increments so that each pair of slots, carrying a related plug, moves in sequence to said transfer station.
